APPARATUS FOR CONNECTING A SOURCE
OF ACOUSTIC WAVES WITH SEVERAL
LISTENERS FOR A SUITABLE TIMEMaxime Baze, Paris, France, assignor to Holding
Internationale Societe Anonyme, Luxemburg,
Grand-Duchy of LuxemburgApplication June 5, 1931, Serial No. 542,362, and
in France June 7, 1930

3 Claims. (Cl. 179—1)

The present invention relates to an arrangement enabling the use of a State or private telephone system for the transmission of acoustic waves, with a single microphone transmitter, to a 5 certain number of subscribers at a time, and in which the listeners will have no connection with one another, and hence cannot interfere with the listening or make it impossible.

For this purpose, the said arrangement comprises a device for amplifying the waves of the 10 acoustic source, in whose circuit are comprised various primaries of transformers corresponding to the number of listeners in question, and each of said primaries acts upon a secondary connected with a subscriber's line.

This connection is made automatically by a 15 relay, after the central telephone employee has placed the subscriber in the circuit, said relay cooperating with other relays in order to operate 20 the devices for the control of the number, quality, duration, and distribution of the communications.

In such conditions, if for instance the 25 transformers have the ratio of 1 to 1, with the use of 100 transformers, the ratio of transformation, which is 100:1 with reference to the source of acoustic waves, is only 1:100 as concerns a subscriber who speaks, and thus the energy transmitted is practically null, and this subscriber 30 cannot be heard by the other listeners, and in addition the impedance of the circuit comprising the primary of the transformers, is increased by the resistance of the filament-plate space of the last amplifying valve in use.

35 The accompanying drawings show by way of example an embodiment of the invention.

Fig. 1 is a diagrammatic view of the arrangement of the transformers.

Fig. 2 shows the details of the controlling 40 relay used for each subscriber.

Fig. 3 shows the amplifier.

Referring to Figure 1, the telephone wires 1, 2 of each subscriber may be connected, by the transmitter, respectively with the wires 3, 4, connected to the contacts 5, 6; said contacts, as will be further disclosed, are automatically brought against the two ends of the wires of a secondary winding of a transformer 8.

All of the primary windings 9 of said 50 transformers are connected together and are also connected by wires 11—12 with an amplifying device A provided with a microphone transmitter 10, for instance, which is spoken into by a speaker.

55 It is thus observed that as long as the contacts 5—6 close the circuit, the corresponding subscriber will hear the speaking.

In order to regulate the time of the listening and to provide for its proper control, the arrangement shown in Figure 2 is employed; the poles

indicated correspond to the poles of the battery of the telephone central.

To the wires 3—4 are connected the respective ends of the winding 11' of a relay 12', with a condenser 13 interposed, and thus when the subscriber is connected to the wires 3—4, the alternating current for the call, which is sent by the central, will energize the said relay.

Thus the contact 14 is attracted, and the circuit of the winding 15 of a relay connected to the negative pole will be closed at the same time that the winding 28 of relay 12 is energized, said contact 14 being connected with a contact 17 to the positive pole which is in contact at this time.

When the relay 16 is thus energized, the contact 75 13 is attracted, and it closes the circuit of the winding 19 of a relay 20, which gives an impulse

to the meter 21 for the communications. At the same time, the relay 12 attracts the contact 22 connected to the positive pole, and the electric 80

current starts a clockwork device 23 which is adapted to move contact 24 (connected to the negative pole) toward the left, immediately upon being started, and to bring it back to its initial position after a predetermined interval of time.

Consequently, as soon as clockwork device 23 has been started the winding 25 of a relay 26, connected to the negative pole, which was short-circuited by said contact 24, is now energized, and it attracts the contacts 27 and 17. It should 85

be understood that the clock work mechanism 23 may be substituted by a mechanism similar to the mechanism employed in the automatic telephone system of the rotary type, more specifically, the type of telephone employing a continuously rotating shaft and electro-magnetic contacts intermittently engageable for making 90

and breaking the circuit.

When the contact 27 is attracted, the circuit 95 of the second winding 29 of the relay 26, connected to the positive pole, is now closed at the contact 25, at the same time as the circuit of a pilot lamp 30 which locates the line in operation.

At the same time, since the circuit is broken 100 at 17, the windings 28 and 15 cease to be energized, and the contact 22 breaks the circuit for the windings 23—25 which are thus out of action;

but since the winding 29 carries current, it holds 105 down the contacts 27 and 17, as well as the contacts 5 and 6 by which the secondary 7 is connected to the line.

In these conditions, as the primary carries the modulated current, the subscriber making the 110 call will receive the musical waves or others.

After three minutes, for instance, according as the apparatus is regulated, the clockwork 23 will bring contact 24 back to its initial position and consequently cut off the current flowing through 115

120

winding 29 of relay 26, thus returning the arrangement to the inoperative position.

The speaker or phonograph are stationed before a single microphone transmitter 10 (Fig. 3) comprised in the plate circuit of a two-electrode valve 31, so as to prevent all distortion arising from the use of devices such as self-induction or capacity; said microphone thus imparts a difference of potential to a device for amplifying 10 musical frequency, which may comprise two double-grid valves 32—33 and a three-grid valve 34. The valve filaments are supplied by a 4-volt battery 35, the plates of the valves 32—33 by a 120-volt battery, and the plate of the valve 34 by 15 a 200 volt battery 37. The plate of the valve 31 is supplied at 80 volts by a battery 38.

The speaker is enabled to observe at each instant the quality and the power of the transmitted waves, by means of telephone listener 39 20 which is branched upon the transmission line by means of a transformer 11, 12.

The speaker is further advised that a subscriber has made a call, by the deflection of a milli-ampere meter 41. For this purpose, the 25 25 turn of all the valves 30 (Fig. 2) to the battery takes place by means of an ammeter shunt 42.

The difference of potential at the ends of this shunt is transmitted by a line to a milli-ampere meter 41 mounted on the speaker's desk. The 30 30 meter 41 is, of course, of conventional construction and does not need any further description. One communication is indicated by a deflection of the pointer by a scale-division, two communications by two divisions, and so on.

35 Obviously the aforesaid arrangement can be used for a wide variety of purposes, and for instance for the voice of a speaker, for the broadcasting, over a wire, of received radio communications or the broadcasting of communications 40 40 which are not in normal connection with the apparatus, and the like.

The installation may employ the city lines, or 45 45 interurban or private lines, and it can be used for advertising, news, transmission of orders, or the like.

I claim:

1. In an ordinary telephonic system including a plurality of subscriber's lines each connected 50 50 with a subscriber's station provided with an ordinary telephone set respectively, a transmission distributing station in said telephonic system adapted to be called in the ordinary way from any of the subscriber's stations and comprising in combination, a microphone, electric amplifying means connected with said microphone, an output circuit for said amplifying means, a plurality of transformers having their primary windings inserted in series in said circuit, and means for connecting the subscriber's lines with the secondary windings of said transformers respectively.

2. In an ordinary telephonic system including a plurality of subscriber's lines each connected with a subscriber's station provided with an ordinary telephonic set respectively, a transmission 65 65 distributing station in said system adapted to be called in the ordinary way from any of the subscriber's stations and comprising in combination, a microphone, electric amplifying means connected with said microphone an output circuit for said amplifying means, a plurality 70 70 of transformers having their primary windings in-

serted in series in said circuit, a plurality of call circuits for said subscriber's lines, means, connected with said call circuits, for establishing connections between said lines and the secondary windings of said transformers respectively, and means for cutting off said connections a predetermined time after they have been established. 80

3. In an ordinary telephonic system including a plurality of subscriber's lines each connected with a subscriber's station provided with an ordinary telephone set respectively, a transmission distributing station adapted to be called in the ordinary way from any of the subscriber's stations, comprising in combination, a microphone, electric amplifying means connected with said microphone, an output circuit for said amplifying means, a plurality of transformers having their primary windings inserted in series in said circuit, a plurality of call circuits for said subscriber's lines respectively, a relay for each subscriber's line adapted to connect said line with the secondary of one of said transformers, a clockwork device for controlling said relay, and a second relay connected to the call circuit of the subscriber's line for starting said clockwork device, whereby the first mentioned relay connects the subscriber's line with the secondary winding of one of the transformers when a call is made in said line, and cuts off the connection a predetermined time thereafter. 95

4. In an ordinary telephonic system including a plurality of subscriber's lines each connected with a subscriber's station provided with an ordinary telephone set respectively, a transmission distributing station adapted to be called in the ordinary way from any of the subscriber's stations, comprising in combination, a microphone, electric amplifying means connected with said microphone, an output circuit for said amplifying means, a telephone receiver coupled with said circuit whereby the quality and the power of the emission can be tested, a plurality of transformers having their primary windings inserted in series in said circuit, and means for connecting said subscriber's lines with the secondary windings of said transformers respectively. 100 105

5. A transmission distributing station according to claim 1 in which the electric amplifying means are connected to the microphone through a two electrodes valve in the plate circuit of which said microphone is inserted. 110 115

6. A transmission distributing station according to claim 1 in which there is provided a two electrodes valve in the plate circuit of which said microphone is inserted, for connecting said microphone to said electric amplifying means, said amplifying means including two two-grid valves and a three-grids valve. 120 130

7. A transmission distributing station according to claim 3, further comprising a lamp, a circuit for said lamp, and means, operatively connected with the first relay and with said clockwork device for closing the last mentioned circuit when the clockwork device is started. 135

8. A transmission distributing station according to claim 3, further comprising a counter, relay for operating said counter, and means, operatively connected with the first mentioned relay, for operating the third mentioned relay every time said first mentioned relay is energized. 140 145
